UNITED STATES PATENT OFFICE.

FRANK P. GARDNER, OF BOSTON, MASSACHUSETTS.

NEEDLE-GUARD FOR SEWING-MACHINES.

1,324,736.

Specification of Letters Patent.

Patented Dec. 9, 1919.

Application filed March 22, 1918. Serial No. 224,061.

To all whom it may concern:

Be it known that I, FRANK P. GARDNER, a citizen of the United States, residing at Boston, county of Suffolk, State of Massachusetts, have invented a certain new and useful Improvement in Needle-Guards for Sewing-Machines, of which the following is a specification, reference being had therein to the accompanying drawings.

10 The invention relates to a needle guard attachment for sewing machines to protect the fingers of the operator against being injured by the needle during the operation. It is obvious that where the needle is unguarded there is a danger that the careless operator while feeding the work may allow his fingers to come into the path of movement of the needle and become severely injured. The object of the present invention

15 is to provide a protecting device which shall be a sufficient guard to render it impossible for the operator to get his fingers into the path of the needle and at the same time to not interfere with the proper view of the

20 work.

The invention will be fully understood from the following description when taken in connection with the accompanying drawings and the novel features thereof will be 30 pointed out and clearly defined in the claims at the close of this specification.

In the drawings, Figure 1 is a side elevation of a portion of the working parts of a sewing machine showing a device embodying the invention attached to the presser foot.

Fig. 2 is a front elevation of a portion of the operative parts shown in Fig. 1 showing the device embodying the invention.

40 Fig. 3 is a plan view of the presser foot and the protector attachment embodying the invention attached thereto.

Fig. 4 is a side elevation of the protector or guard embodying the invention detached.

45 Referring now to the drawings, 1 represents a portion of the frame work or arm of a sewing machine, 2 the feed, 3 the needle bar provided with a needle 4, and 5 the presser bar to which is attached the presser foot 6 all of which as thus far referred to may be of any well known form of construction. The guard 7 is preferably in the form of an open or split ring forming a guard rail around the path of movement of

50 the point of the needle 4 of sufficient diameter to allow ample space around the

needle within the inclosure, and having an opening 8 on one side of sufficient width to permit a ready view of the needle but yet being sufficiently narrow so that there is 60 no possible danger of the finger getting in through the opening into the path of the needle. The guard should preferably extend for at least three-fourths of the way around the needle. This guard is suitably 65 attached to the presser foot or to the presser bar so that it will be held in proper position. It is open at top and bottom to allow free movement of the needle. The lower end of the guard is preferably elevated a 70 little above that portion of the presser foot containing the slot through which the needle passes and it should preferably extend upward a sufficient distance so that in the upward stroke of the needle the point 75 of the needle will clear the guard only just enough to permit threading of the needle, but so slightly above that it will be impossible for the finger of the operator to come in contact with the point. The exact 80 height is immaterial so long as the point is properly protected, so that the operator can not get his finger under the point of the needle.

In the form of device shown the guard 85 7 has an attaching bracket portion having an arm 18 which lies over the upper face of the bent portion 9 of the presser foot shank and which terminates in two vertical grooved clips 10, 10 which embrace the two 90 opposite edges of the vertical web 11 of the presser foot shank. These clips 10, 10 may be crimped over the web 11 sufficiently tight to hold the guard against displacement while the machine is in operation or 95 may be fastened in any suitable manner. Preferably there are two side fingers 12, 12 which extend downwardly from the arm 18 and straddle the arm 9 of the presser foot shank to aid in preventing lateral displacement of the guard. Preferably the guard has a downwardly depending tab portion 13 on that side which is toward the short toe of the presser foot and which extends down a little lower than the remaining portion of the guard, on account of the greater exposed space above the short toe of the presser foot.

100 I have shown the guard 7 as being of a semi-cylindrical form and I regard that as 110 the preferred form. It may however be polygonal or any other suitable form as I do

not regard the exact contour as being material to the invention.

Also while I have shown and described one means for connecting the guard to the presser foot any suitable connecting means 5 may be employed. Also it may be attached either to the presser foot itself or to the presser foot bar. The form and means of attachment will preferably be adapted to 10 the particular form of presser foot, as there are various forms of presser foot. The essential feature of the invention is a guard or shield which surrounds or partially surrounds the needle near its lower end.

15 What I claim is:

1. A needle guard attachment for sewing machines comprising a semi-ring guard member which guards the path of movement of the needle, a bracket portion having grooved wing members for engagement with a presser foot bar, a neck portion which connects the said guard member with the said grooved wing members, said neck 20

portion being shaped to rest against a presser foot shank and fingers which project laterally from opposite sides of said neck and are bent to straddle the said presser foot shank. 25

2. A separable needle guard attachment for sewing machines, made of a single sheet 30 of metal bent to form a semi-ring guard member which surrounds the path of movement of the needle on at least three sides, the attaching portion being slotted vertically and adapted to engage by a sliding 35 movement with a presser foot bar, a neck portion which connects the said slotted attaching portion with the guard member and is shaped to rest upon a presser foot shank, and fingers which project laterally from 40 opposite sides of the said neck member and are bent to straddle a presser foot shank and engage the sides thereof.

In testimony whereof I affix my signature.

FRANK P. GARDNER.
